TRACK IN A MUSIC PLAYING TOY RAILROAD

Matsuzo Kosuge, 1516 Okudohoncho, Katsushika-ku,
Tokyo, Japan

Filed Dec. 14, 1965, Ser. No. 174

Term of patent 14 years

(Cl. D34—15)

Fig. 1.

Fig. 2.

FIG. 1 is a front view of a track for a music playing toy railroad showing my new design;

FIG. 2 is a top view of the track shown in FIG. 1;

FIG. 3 is a bottom view of the track shown in FIG. 1; and

FIG. 4 is a cross-section of the track shown in FIG. 2 along line IV—IV of FIG. 2.

I claim:

The ornamental design for a track in a music playing toy railroad, as shown.
